(57) CLAIM

The ornamental design for a shoe as shown and described.

DESCRIPTION

FIG. 1 is a front perspective view of a shoe showing my new design;

FIG. 2 is a top view thereof; and,

FIG. 3 is a opposite front perspective view thereof.

The broken line immediately adjacent to and surrounding the photographic region represents a peripheral boundary and forms no part of the claimed design. The broken lines depicting the remainder of the shoe form no part of the claimed design.
